COMBINATION COT AND MASSAGING UNIT

Louis Seaman and Solomon Karp, Los Angeles, Calif.

Application May 9, 1958, Serial No. 50,822

Term of patent 14 years

(Cl. D83—1)

The characteristic features of our design for a combination cot and massaging unit reside in the central portions of the article, as shown.

We claim:

The ornamental design for a combination cot and massaging unit, as shown and described.
